UNITED STATES PATENT OFFICE.

FREDERICK STAPP, OF DENVER, COLORADO.

RIVETING MANDREL.

Application filed December 28, 1925. Serial No. 77,984.

This invention relates to improvements in riveting mandrels of the type employed in the manufacture of tubular articles having riveted seams.

5 In the manufacture of pipes, cylindrical tanks, small boilers and similar articles, the seams are often riveted. This operation is usually accomplished by placing a rivet on the upper surface of a long mandrel that is 10 supported at one end and which extends outwardly from the support in the form of a cantilever. The tubular member that is to be riveted is then passed over the mandrel and carefully lowered onto the rivet. If 15 the seam has already been drilled, it is then necessary for the operator to carefully move the pipe from one position to another in an effort to introduce the rivet into the hole; this is a very tedious and difficult operation 20 for the reason that the rivet is concealed and rests loosely upon the mandrel. If the rivet is moved, however slightly, in a sidewise direction, it will topple over, which means that the pipe will have to be removed and the 25 rivet replaced after which another try must be made. It can readily be seen that the proper placing of the article to be riveted, so as to get the invisible rivet into the desired location is a difficult task and it often 30 happens that several minutes are required to place a single rivet.

It is the object of this invention to produce an apparatus of this type that is so constructed that the article to be riveted can 35 be slipped over the mandrel before any rivet is put into place thereon and which shall be provided with means for introducing the rivets into the same while the article is still in place over the mandrel. It is also an object of this invention to produce an article 40 of this type that shall have means for accurately indicating the exact position of the rivet so that the operator can always tell the exact spot of the article that lies directly 45 over the rivet.

The above, and other objects that may become apparent as the description proceeds, are attained by means that I will now describe in detail, reference for this purpose 50 being had to the accompanying drawing in which the preferred embodiment of the invention has been illustrated and in which:

Fig. 1 is a top plan view of my improved device;

55 Fig. 2 is a side view of the invention, parts being broken away to better disclose the con-

struction and a pipe being shown in place about the mandrel;

Fig. 3 is a section, to a somewhat enlarged scale, taken on line 3—3, Fig. 1;

Fig. 4 is a section taken on line 4—4, Fig. 3; and

Fig. 5 is a detail view, partly in section, showing the manner of attaching the rivet to the feeding means.

Numeral 1 indicates a support such as the top of a work bench. The top of this bench is a convenient distance above the floor. Secured to the bench 1 is my improved riveting mandrel which consists of a base 2 that 70 is fastened to the bench 1 by means of bolts 3. Formed integral with the base 2, or rigidly secured to it in some suitable way, is a cylindrical mandrel 4, which may be of cast steel or other suitable material. This 75 mandrel has been shown as of circular cross section, which is considered preferable, but any other cross sectional shape may be employed. It is, however, preferable to have the upper surface of the mandrel slightly 80 convex. The base 2 has a wall 5 extending upwardly along its front edge and this wall has an opening 6 directly over the top of the mandrel 4. An upstanding ridge or support 7 extends rearwardly from the wall 5 and forms, in effect, a prolongation of the mandrel 4. A dovetail groove 8 extends rearwardly from the point 9, near the outer end of the mandrel 4 to the rear end of the support 7. A strap 10 of steel, iron or other 90 material is slidably mounted in the groove 8 and has one end provided with a notch 11 which is adapted to receive the shank 12 of a rivet. It will be noted that the end of the strap 10 adjacent the notch 11 is 95 cupped upwardly in the manner indicated by numeral 13 in Figs. 3 and 5 so as to provide a recess for receiving the head of the rivet. The inclined sides of the groove 8 terminate at 9 and from thence the bottom of the slot inclines upwardly in the manner indicated by numeral 14 in Fig. 3. The strap 10 has a stop 15 that is so placed 100 as to engage the end of the upright 7 so as to limit the outward movement of the strap whereby the rivet can be positively located. The end of the strap 10 opposite from the notch 11 has a portion 16 that is bent so as to form a handle that can be 105 grasped for moving the strap. The strap can be moved towards the right into a position like that shown in Fig. 5 in which posi-

110

tion the rivet 12 can be introduced into the notch 11, after which the strap can be pushed towards the left until it reaches the position shown in Figs. 2 and 3, where the rivet 5 will be quite firmly held in the manner shown. A pipe 17 can now be slipped over the mandrel 4 in the usual manner. It is evident that when the pipe 17 is in place, as shown in Fig. 2, that the rivet will be 10 hidden and the operator cannot tell just where it is. To enable the operator to locate the exact position of the rivet when the pipe is in place, I have provided an arm 18 that is hinged so that it can be swung about an 15 axis indicated by numeral 19. A pin 20 is secured to the underside of the arm 18 and is so located that when this arm is in the position shown in Fig. 2, the point of this pin will be directly over the rivet 12. It 20 is now evident that when the pipe 17 is in place and conceals the rivet, it is only necessary to swing the arm 18 down until the point of the pin 20 rests upon the pipe; this will then indicate the exact position of 25 the rivet. If the material has been drilled and it is desired to insert a rivet into the hole, it is only necessary to bring the hole into position underneath the pin 20, when it will be directly over the rivet 12. In 30 order to hold the arm 18 out of the way while the rivet is headed I have provided a latch which has been illustrated as consisting of a short inclined arm 21 that is fastened to the arm 18 near the hinge 19 and 35 which cooperates with the spring 22 to hold the arm in the position indicated by dotted lines in Fig. 2. After the rivet has been inserted into the opening in the pipe, an assistant may withdraw the strap until it 40 occupies the position shown in Fig. 5 and put another rivet in place. This rivet may be quickly moved to the position shown in Fig. 3, without removing the pipe. With this apparatus no time is wasted in introducing the rivets into the holes provided 45 for them or in locating the exact position of the rivet with respect to the pipe whereby a large amount of time can be saved on each operation.

50 It is understood that the device shown is

illustrative only and is to be construed as such and not in a limiting sense.

Having now described the invention what is claimed as new is:

1. A device for use in riveting tubular 55 articles comprising, in combination, a support, a mandrel secured at one end to said support and projecting outwardly therefrom, said mandrel having a dovetailed groove extending longitudinally thereof and 60 located in its upper surface, a strap slidably mounted in said groove and having means at one end for holding a rivet, and a stop at the other end for determining the 65 maximum distance that the strap can be moved in one direction whereby a rivet may be moved to a predetermined position, an indicator arm hingedly connected at one end to said support, said arm carrying a pin and being substantially straight beyond the 70 hinge in the direction of the pin, the length of the said arm from the axis of its hinge to the pin being predetermined so that the rivet when the strap is extended to the maximum 75 distance, is in alignment with the pin, and means for holding the indicator arm in the inoperative position.

2. In a riveting device, the combination of 80 a support, a mandrel secured at one end to said support and projecting outwardly therefrom, said mandrel having a groove extending longitudinally thereof and located 85 in its upper surface, a strap slidably mounted in said groove and having means at one end for holding a rivet, and a stop at the other end for determining the maximum 90 distance that the strap can be moved in one direction whereby a rivet may be moved to a predetermined position, an indicator arm hingedly connected at one end to said support, said arm carrying a pin, the length of said arm from the axis of its hinge to the pin being predetermined so that the rivet 95 when the strap is extended to the maximum distance is in alignment with the pin, and resilient means for holding the indicator arm in the inoperative position.

In testimony whereof I affix my signature.

FREDERICK STAPP.
